George H. Frost, Ashland, Ohio, assignor to John Oster
Manufacturing Co., Milwaukee, Wis., a corporation of Wisconsin

Filed June 14, 1965, Ser. No. 85,704

Term of patent 14 years

(Cl. D86—10)

Fig. 1

Fig. 2

FIG. 1 is a side elevational view of a hair dryer showing my new design;

FIG. 2 is a top view thereof;

FIG. 3 is a front elevational view thereof; and

FIG. 4 is a reduced view similar to that of FIG. 1 but showing the hair dryer in open position.

The dominant features of the design reside in those portions shown in full lines.

I claim:

The ornamental design for a hair dryer, as shown and described.
